[57] CLAIM

The ornamental design for a retractable roof-top seal for a vehicle, as shown and described.

DESCRIPTION

FIG. 1 is a top perspective view of a retractable roof-top seal showing my new design;

FIG. 2 is an enlarged sectional view taken along line 2—2 of FIG. 1 and showing the cross-section of the front leg thereof;

FIG. 3 is an enlarged sectional view taken along line 3—3 of FIG. 1 and showing the cross section of a side leg thereof; and,

FIG. 4 is a top plan view thereof on a reduced scale in position of use on an automobile which is shown in broken lines for illustrative purposes only and forms no part of the claimed design.
